UNITED STATES PATENT OFFICE

THOMAS L. KELLEY, OF SALEM, SOUTH DAKOTA

SAFETY LINE TERRET

Application filed August 2, 1928. Serial No. 296,991.

This invention relates to a harness terret and has for its primary object to provide, in a manner as hereinafter set forth, a device of this character of improved construction, in which one of the reins may be inserted and held against any but longitudinal movement.

A further object of the invention is to provide a terret having a pair of spaced posts between which the rein is designed to be positioned on edge, these posts being rigidly secured within a ring which is split obliquely with respect to its axis.

The invention will be best understood from a consideration of the following detailed description taken in connection with the accompanying drawings forming part of this specification with the understanding, however, that the invention is not confined to any strict conformity with the showing of the drawings but may be changed or modified so long as such changes or modifications mark no material departure from the salient features of the invention as expressed in the appended claim.

In the drawing:—

Figure 1 is a front elevational view of the terret embodying the present invention;

Figure 2 is a top plan view of the same;

Figure 3 is a vertical sectional view taken upon the line 3—3 of Figure 2.

Referring to the drawing in detail wherein like numerals of reference indicate corresponding parts throughout the several views, the numeral 1 indicates the body of the terret structure which is of ring formation as shown. This ring is relatively broad and is provided with a base 2 from which extends a threaded stud 3 by means of which the terret is mounted in position upon the saddle or similar part of the harness structure.

Within the ring there is secured a pair of pins or posts 4 arranged in spaced upwardly diverging relation and upon opposite sides of the axis of the ring and extending in the same general direction as the stud 3 by means of which the ring is mounted in position.

The ring body 1 is split as indicated at 5 on a line oblique to the axis thereof and diametrically opposite the base 2.

When the present terret structure is in posi-

tion, the ring is so arranged that the faces thereof are positioned transversely of the horse's body and a rein is placed in position therein by extending the same edgewise through the slot 5 and allowing it to come to rest on edge between the posts 4.

It will be readily seen that with a terret of the present character in which the posts are arranged in upwardly diverging relation, the rein (not shown) will have free movement through the terret and the terret will act to prevent the rein buckles from passing therethrough thereby maintaining the reins in position when the same are slackened.

From the foregoing, it will be readily seen that the herein described terret is of simple construction, has no moving parts to become rusty and noisy, and may be inexpensively manufactured.

Having described my invention what I claim is:—

A terret of the character described, comprising a relatively broad ring body, means extending from the peripheral face of the ring for mounting the same in upright position, a pair of spaced upright posts secured within said ring and arranged in upwardly diverging relation, and means for introducing a rein to position between said posts, consisting of a split made through the ring body at an oblique angle with respect to the axial line thereof, the upper end of each post being positioned a substantial distance to one side of the split.

In testimony whereof I hereunto affix my signature.

THOMAS L. KELLEY.
